UNITED STATES PATENT OFFICE.

FRANK POKORNY, JR., OF NEW YORK, N. Y., ASSIGNOR OF ONE-HALF TO FRANCIS W. KEEGAN, OF NEW YORK, N. Y.

AIR HEATER.

Application filed August 14, 1920. Serial No. 403,829.

To all whom it may concern:

Be it known that I, FRANK POKORNY, Jr., a citizen of the United States, and resident of borough of Manhattan, in the city, county, and State of New York, have invented certain new and useful Improvements in Air Heaters, of which the following is a specification.

This invention relates to means for pre-heating the air supplied to carburetors for the production of fuel and air mixtures, and my improvement consists of a simple device arranged for attachment to the exhaust manifold, whereby heat from the exhaust gases, radiating from the surface of said manifold, may most efficiently be utilized as the pre-heating agent for air flowing to the carburetor.

Heaters, or stoves, as they are sometimes called, as hitherto used, have been composed of a section of tubing surrounding the exhaust pipe, in spaced relation therewith, to thus provide a confined passage for air flowing to the carburetor, but heating means of this character have not been found efficacious, for the reason that the heating surface by which the passing air is influenced is of insufficient area.

Therefore I have devised a special form of heater which comprises a member adapted to have spaced engagement with the exhaust manifold of an engine to afford a clear passage between said member and the surface of the exhaust manifold, and having delivery connection with the carburetor. This heater member, which I shall call an envelope, is adapted to hold in place between it and the surface of the exhaust manifold a multiple-channel air passage of material which is a good conductor of heat and which divides up the flow of air into a series of relatively thin streams that are each subjected to heat radiation from the divisional walls of said multiple-channel, so that the full volume of air passing between the envelope and manifold becomes more highly heated than would be otherwise possible.

Of course it will be appreciated that with the motor turning over slowly so that the air travelling to the carburetor has a moderate flow rate, naturally the streams of air will be more highly heated than when the motor is running at a higher speed and the flow of air is more rapid, but this is desirable because more highly heated air is re-

quired for a slow running motor than for the same motor when running faster.

The multiple-channel passage device is readily removable from the envelope, because in hot weather its service is not desirable, and an orifice in the envelope, provided with a shutter, permits of temperature regulation suited to seasonal conditions.

Other features and advantages of my invention will hereinafter appear.

In the drawing:

Figure 1 is a side elevation of a portion of an exhaust manifold forming part of an internal combustion engine, and having my air pre-heating means attached thereto.

Fig. 2 is an enlarged section on the line 2-2 of Fig. 1, and

Fig. 3 is a similar view, omitting the corrugated interior member.

In said views let 1 indicate an exhaust manifold as forming part of an internal combustion engine, whose other portions are not herein shown. Since it is my purpose to utilize heat radiating from the surface of the manifold whereby to raise the temperature of air passing to the carburetor, I have devised an elbow member having the tubular portion 2 which is intended to connect with a carburetor, to supply air thereto, said portion 2 being an angular extension of a jacket like portion that comprises a vertically curved wall 3, partially surrounding the exhaust manifold and of greater extent than the vertical diameter of the manifold pipe, said wall 3 having upper and lower, return bends, 4, 5, which are provided, respectively, with opposed, parallel edges 6, 7, lying in a vertical plane rearwardly of wall 3, the said edges 6, 7, being spaced apart sufficiently to permit them to lie, respectively upon or near the upper and lower surfaces of the manifold, to thus provide a clearance 8 between wall 3 and the manifold. The entrance 9 to said clearance is directed, in motor vehicle practice, towards the rear surface of the usual radiator, that it may receive currents of air, which has been heated by passing over the radiator.

The air thus received within the envelope formed by the wall 3 and the manifold is raised in temperature while passing therethrough. But in cold weather I have found the degree of pre-heat thus provided insufficient for efficient carburation purposes. Therefore I introduce within the envelope a

convoluted or corrugated sheet 10 of metallic material which is a good conductor of heat, whose corrugations, or return bends provide a series of parallel passages 11 within the envelope, that cause the flow of air to be divided up into a number of separated streams, each travelling between walls composed of adjacent folds or bends of the sheet.

5 The sheet 10 being flexible, is able in its crimped or corrugated form to conform to the contour of the enclosure provided by the envelope, and the folds of said sheet being tensionally contracted, it fits snugly between the return bends 4, 5 of said envelope.

10 15 The depth of the corrugations is of such extent that they fill out the space between the envelope and the manifold surface, by contact with which latter they become very highly heated, due to the conductive nature 20 of the material comprising sheet 10.

A lug 12, projecting inwardly from the wall 3, at the entrance to the envelope serves as a stop to engage with the outer surface of the manifold and thus to maintain the desired space between the wall or envelope 3 and the exhaust manifold. The means shown herein for fastening the pre-heating device to the manifold consists of a strap 13 placed around both the envelope 25 and the manifold, with the ends of said strap flanged and united by a bolt 14.

An aperture 15 is provided in the wall 3 which may be closed partially or wholly by a shutter 16, slidably in guides 17 at opposite edges of said aperture.

Therefore, according to the atmospheric temperature conditions which prevail, so may the device be employed either with or without the corrugated sheet 10, and with the aperture 15 closed, partly open, or fully 40 open.

Variations may be resorted to within the spirit and scope of my invention and parts thereof used without others.

45 I claim:

Preheating means for the air supply to carburetors of internal combustion engines comprising, in combination, an elbow device having a transversely curved portion with oppositely inturned edges and an intermediate, inturned spacing lug adapted to set against the exhaust manifold of an engine to provide an air passage between said portion and manifold, an angularly disposed tubular portion to connect with the carburetor, the forward end of the curved portion being open to admit air for passage through the tubular portion, a corrugated sheet of heat conductive material fitting between the curved portion and the manifold 50 to provide a series of parallel channels for the sub-division of the flowing air into separate streams, and a controllable opening in the curved portion to vary the temperature therein.

60 Signed at borough of Manhattan in the city, county, and State of New York this 6th day of August A. D. 1920.

65 FRANK POKORNY, Jr.
